UNITED STATES PATENT OFFICE.

CARL G. STRANLUND, OF MOLINE, ILLINOIS, ASSIGNOR TO DEERE & COMPANY, OF MOLINE, ILLINOIS, A CORPORATION OF ILLINOIS.

CULTIVATOR.

Application filed April 19, 1921. Serial No. 462,618.

This invention relates to cultivators and it is an object of the invention to provide an improved means for connecting the cultivating rigs to the frame and for raising and 5 lowering the rigs. A further object is to combine the improved connecting and the raising and lowering means with means for balancing the frame of the cultivator.

Referring to the drawings in which like 10 numerals indicate identical parts.

Figure 1 is a top plan view of my cultivator.

Figure 2 is a side elevation taken on line a—a of Figure 1, and showing the cultivator 15 rigs in lowered position.

Figure 3 is a similar view to Figure 2, but with the cultivator rigs in elevated position.

Supporting wheels 10 are journaled on laterally extending lower portions of an arch 20 axle 11. The arch axle may be in a single piece but in this instance I prefer to make it in two parts, each having an upper portion pivotally mounted in a transverse horizontal bearing member 12 and held from end- 25 wise movement in relation to the member 12 by set collars 13, secured to the bearing 12 and having extensions 14 engaging lips 15 of set collars 16 secured to the axles 11. Forwardly extending and converging frame 30 members 17 are secured at their rear ends by bolts 18 to castings 19 secured to the bearing member 12. At their forward ends the frame members 17 are secured by bolts 20 and 21 to a casting 22. Intermediate their 35 lengths the frame members 17 are further secured by means of a bracing member 23 to which are secured rearwardly extending converging seat bars 24 which rest, intermediate their length, on the member 12 and 40 on their rear portions carry a seat 25. Foot rests 26 are secured to and depend from the member 12 and are braced by means of a U-shaped member 27 attached to each of the foot rests 26 and to the brace member 23.

45 A draft pole 28 extends through a suitable opening in the casting 22 and is attached at its rear portion to a bracket 29 secured to the brace 23.

The horizontal connecting portion of an 50 arch member 30 is journaled for fore and aft swinging movement in a suitable transverse bearing in the casting 22. The arch member 30 has the usual depending members or legs and in this instance integral laterally ex- 55 tending lower portions which form trans-

verse horizontal axes upon which are journaled the forward portions of cultivator rigs 31 so that said rigs may swing vertically independently of each other. Obviously the arch 30 functions as a pair of links 60 which are adapted to swing fore and aft in unison. The cultivator drag bars or rigs 31 are of a well known type and carry the usual earth working devices 32. Endwise movement of the rigs 31 in relation to the arch 65 30 is prevented by means of set collars 33 which, however, permit the rigs to be adjusted laterally to accommodate various widths of rows.

Fore and aft swinging movement of the 70 arch member 30 is controlled through a rod 34 pivotally attached at one end to one of the laterally extending lower portions of the depending members of the arch and at the other end to a lever 35 which is pivotally 75 mounted on a sector 36 secured to one of the castings 19. The lever 35 carries the usual latch and dog device adapted to engage one of a series of notches in the sector 36.

Members in the form of links 37, parallel 80 with the depending members or legs of the arch 30, and spaced therefrom longitudinally of the machine are pivotally connected at their lower ends with eye bolts 38 secured to the rigs 31. At their upper ends the links 37 are pivotally connected to levers 39 which are pivotally mounted on sectors 40 secured to the castings 19. The members or links 37 being parallel with the depending members or links of the arch 30 effect a vertical trans- 85 latory movement of the rigs when said members are swung fore and aft by the actuation of the lever 35, i. e., the rigs maintain their horizontal position while being raised and lowered, and they may be set normally in 90 various working positions by means of the locking devices associated with said lever. The levers 39 also carry the usual latch and dog device adapted to engage with notches in the sectors 40. The levers 39 are for the 95 purpose of swinging either of the rigs 31 around the transverse horizontal axis formed by the laterally extending lower portions of the arch 30 to raise or lower them. As a lever is provided for each rig, either rig can 100 be raised or lowered independently of the other.

Connecting rods or links 41 are pivotally connected at their rearward ends to the lower portions of castings 42 secured to the 110

2
axle 11. Near their forward ends the connecting rods 41 are pivotally attached to the laterally extending lower portions of the arch 30 and are held from transverse movement on the arch by means of pins 42^a. It is evident that the depending members of the arch 30 and the connecting rods 41 form a toggle and by swinging the arch 30, by means of the lever 35, the axle members 11 will be 5 swung in their bearing in the member 12 and the supporting wheels 10 will be moved longitudinally of the frame rearwardly for the purpose of compensating for the shifting of the weight when the cultivator rigs are 10 raised or lowered.

The forward ends of the connecting rods 41 are, in this instance, each formed with an eye to which eyes are secured draft links 43 which are also connected with the lower 15 portions of depending draft bars 44. The upper ends of the draft bars 44 are pivotally connected with a horizontal draft bar 45 secured to the pole 28 by a bolt 46. In suitable holes in the draft bars 44 the usual singletrees 47 are connected by means of 20 hooks 48.

Assuming the various parts to be in the 25 position shown in Figure 2, it is evident from the foregoing that by stroking the lever 35 downwardly the arch 30 will be swung rearwardly and upwardly around its bearing in the casting 22 and the links 37 will be swung rearwardly and upwardly around their pivots in the levers 39 in parallel 30 relationship with the arch members 30 thereby raising the cultivator rigs while they maintain their horizontal position, and at the same time, by reason of the arch 30 being connected with the axle members 11 by means of the rods 41, the axles 11 will be 35 swung rearwardly around their pivot in the bearing member 12, thus balancing the frame. At the conclusion of this movement the various parts assume the positions 40 shown in Figure 3.

By stroking the lever 35 upwardly, from the position shown in Figure 3, the actions of the various parts will be the reverse to those just described and the parts will again 45 assume the position shown in Figure 2. Not only is provision made for adjusting the gang bars and their tool sets at any time in horizontal parallelism, and for holding them at either of several working horizontal 50 planes, for different duties, but provision is also made for quickly lifting the tools in horizontal parallelism from any of their variable working planes to their highest elevation without destroying their adjustment. 55 No matter what work they are doing, whether cultivating deeply or penetrating only to lines of lesser depth, they can, when the machine reaches the end of a traverse across the field, be quickly lifted by a single 60 movement of the operator, and then be as 65

quickly returned by a single movement to their said adjusted positions. And the gang bars, respectively, may be differently adjusted, as circumstances require, and their adjusting devices can be locked in position, 70 and yet all of the tools can be simultaneously elevated, as when the machine is to be turned, and, after turning, the tools of each set can be again lowered to occupy the working position to which they had been previously adjusted. 75

Moreover, as the maintaining of horizontal parallelism causes bodily movement forward or backward of the tool sets, with a corresponding throwing of the apparatus 80 out of balance, provision is made for throwing the wheels in such way as to maintain the predetermined balance. The arms or links which are interposed between the swinging front arch and the wheel carriers 85 move the wheels in correspondence with the tool bar movement, the arms or links being moved toward or from alinement with the arch legs and the wheels being moved forward or backward in correspondence with 90 the movement, bodily of the tool bars. Said arch legs and the links 41 are brought into alinement when the rigs are translated to the highest position shown in Fig. 3 and then become effective to lock the parts in 95 such position so that the lever 35 is relieved of strains that it would otherwise have to withstand.

I claim:

1. In a cultivator of the type described, the combination of a frame, supporting wheels therefor, a tool carrying rig, parallel members suspending said rig at longitudinally separated points from the frame and arranged to swing fore and aft, to translate the same vertically, a lever mounted on the frame, means connecting said lever with said members for swinging the same in unison by the actuation of said lever, and means operable to swing said rig vertically about a transverse axis. 100

2. In a cultivator of the type described, the combination of a frame, supporting wheels therefor, a tool carrying rig, parallel members suspending said rig at longitudinally separated points from said frame and arranged to swing fore and aft to translate the same vertically, a lever for actuating said members, means for locking said lever to hold said rig normally in either of several working positions, and means operable independently of the actuation of said lever to swing said rig vertically about a transverse axis. 115

3. In a cultivator of the type described, the combination of a frame, supporting wheels therefor, tool carrying rigs, two parallel members connected with each rig at longitudinally separated points and with the frame, to swing fore and aft, means operable 120 125 130

to swing said members in parallelism to translate the rigs vertically, and means for swinging said rigs about transverse axes independently of each other and of the actuation of said translatory means.

4. In a cultivator of the type described, the combination of a frame, supporting wheels therefor, a tool carrying rig, parallel members connected with said rig at longitudinally separated points and with the frame, to swing fore and aft, means operable to swing said members in parallelism to translate the rig vertically, and a lever associated with said rig and connected with one of said parallel members for swinging said rig vertically about a transverse axis independently of the operation of said translatory means.

5. In a cultivator of the type described, the combination of a frame, an arched axle pivotally connected with said frame to swing fore and aft, wheels mounted on said axle, tool carrying rigs, parallel members connecting said rigs with said frame and adapted to swing fore and aft to translate the rigs vertically, a lever mounted on the frame, means connecting said lever with the rigs for swinging said members in parallelism, and means actuated by the swinging of said members for rocking said axle.

6. In a cultivator of the type described, the combination of a frame, an arched axle pivotally connected with said frame to swing fore and aft, wheels mounted on said axle, tool carrying rigs, parallel members connecting said rigs with said frame and adapted to swing fore and aft to translate the rigs vertically, a lever mounted on the frame, means connecting said lever with the rigs

for swinging said members in parallelism, means actuated by the swinging of said members for rocking said axle, and means for vertically adjusting the rigs independently of their translatory movement.

7. In a cultivator of the type described, the combination of a frame, an arched axle pivotally connected with said frame to swing fore and aft, wheels mounted on said axle, tool carrying rigs, parallel members connecting said rigs with said frame and adapted to swing fore and aft to translate the rigs vertically, a lever mounted on the frame, a rod connecting said lever with the forward portion of the rigs and operable by said lever to swing said members in unison, and means actuated by the swinging of said members to rock said axle.

8. In a cultivator of the type described, the combination of a frame, an arched axle pivotally connected with said frame to swing fore and aft, wheels mounted on said axle, tool carrying rigs, a front arch pivotally mounted on the frame and having depending members connected with said rigs, links connected with the frame and with said rigs to swing fore and aft in parallelism with said members to translate the rigs vertically, a lever mounted on the frame, a rod connecting said lever with the forward portion of the rigs and operable by said lever to translate the rigs vertically, and connecting rods between the depending members of said front arch and the lower portions of the arched axle and movable into alinement with said members when the rigs are raised to their highest position.

CARL G. STRANDLUND.

CERTIFICATE OF CORRECTION.

Patent No. 1,644,042.

Granted October 4, 1927, to

CARL G. STRANDLUND.

It is hereby certified that error appears in the printed specification of the above numbered patent requiring correction as follows: Page 2, line 39, for the words "axle members" read "axles" and line 40, for the word "axles" read "axle members"; page 3, line 3, claim 3, after the word "rigs" insert the word "vertically"; and that the said Letters Patent should be read with these corrections therein that the same may conform to the record of the case in the Patent Office.

Signed and sealed this 20th day of December, A. D. 1927.

Seal.

M. J. Moore,
Acting Commissioner of Patents.
